UNITED STATES PATENT OFFICE.

EDWARD REUKAUF, OF PHILADELPHIA, PENNSYLVANIA.

CONTAINER FOR BOXED GOODS.

1,283,902.

Specification of Letters Patent.

Patented Nov. 5, 1918.

Application filed October 31, 1916. Serial No. 128,739.

To all whom it may concern:

Be it known that I, EDWARD REUKAUF, a citizen of the United States, residing in Philadelphia, Pennsylvania, have invented 5 certain Improvements in Containers for Boxed Goods, of which the following is a specification.

My invention relates to containers for boxed goods or goods which are vended from 10 original packages, and while it has been designed more particularly for receiving cigar boxes from which the cigars may be vended from the original package in the usual manner, it may be employed as a container for 15 other forms of boxes, whether original packages or not, having other vendible units. The main object of my invention is to provide a container cabinet or structure which may be mounted upon a counter of a dealer's 20 establishment and support the contained box, whether a cigar box or other structure, in open condition and in such manner that its contents will be exposed to view through a movable glass cover; the ends of the box 25 and its cover being preferably inclosed by glass walls so that the usual advertising labels carried by the box and its cover may serve as the advertising means for the goods themselves and further as a positive identification of the same.

A further object of my invention is to provide a container for vendible units, particularly when employed for cigars or other articles which have a tendency to dry out, 35 with a humidor section, so that the vendible contents of the contained box—cigars or the like—may be kept in the original moist condition which such goods possessed when the box was initially opened.

40 These and other features of my invention are more fully described hereinafter, reference being had to the accompanying drawings, in which:

Figure 1, is a perspective view of one form 45 of container or cabinet within the scope of my invention; the same being shown as inclosing a box of cigars.

Fig. 2, is a sectional view on the line II—II, Fig. 1, and

Figs. 3 and 4, are sectional views similar 50 to Fig. 2, illustrating other forms of containers or cabinets within the scope of my invention.

The container or cabinet shown in Figs. 1 and 2, comprises a structure which may 55 have a metal front wall 1, side walls comprising metal frames 2, with glass inserts indicated at 3, a rear wall 4, and a metal bottom 5 to which said rear wall may be hinged as at 6. Within this container may 60 be placed an original package, which may comprise a box 7 of cigars, with its usual cover 7^a. The container has a bar 8 disposed at the top and toward the rear of the same, which bar may be of metal and to which a 65 pair of frames 9 and 10, are hinged at 11 and 12; said frames carrying glass sections 13 and 14, through which the contained goods and the cover of the box may be viewed.

The frame 9, with its glass 13, overlies the cigars in the box 7, or other vendible units in the package within the container, while the glass plate 14 of the frame 10 overlies the cover 7^a of the box 7, which cover is fully 75 open and extended in substantially the same plane as the open top of the box containing the vendible goods.

The glazed frame 10 receiving the lid 7^a of the contained box 7, is preferably provided 80 with lugs 15 to retain the hinged back wall 4 of the container in closed position when said frame is supporting the box lid 7^a in the open position; said frame 10 being held in the open position by a hook 16 which 85 may be hinged to the bottom 5 of the container in line with the hinge 6 between the same and the back 4, and such hook may engage an eye 17 carried by the upper edge 90 of the frame 10.

The frame 9 which, with its glass section 13, forms a cover for the contents of the contained box 7, may be provided at the side with a handle 20 whereby said cover may be moved on its hinge 11 to lift the 95 same when the contents or any portion of the goods in said box 7 are to be removed, and such cover may have in addition a small

clip 21 at the front edge of the same whereby it may be lifted to permit access to the goods in said box 7.

In order to provide a humidor structure 5 for the container or cabinet, the rear wall 4 of the same may carry a removable perforated shell or casing 25, with a suitable moisture-receiving inclosure 26, which may be of fibrous material; said shell being slidably mounted with respect to said rear wall 4 so as to be capable of removal and insertion at will. For this purpose the wall 4 may have slideways 27 for reception of the flanged ends 28 of the perforated shell 25. 15 As the moistening structure providing the humidor element is preferably carried on the inner face of the hinged rear wall 4, the space between the same and the front wall 1 of the container is designed to be just about 20 large enough to receive a cigar box.

The bottom of the container may have a ledge or projection 30 disposed toward the front and receiving non-scratching sound-deadening pads 31, with a rear leg 32 pivotally mounted at 33 and so constructed as to be held in position to elevate the whole structure at the desired angle, as shown in Fig. 2, said leg having pads 34 of the same character as the pads 31 at the front of the 25 structure, whereby the container or cabinet may be placed upon a counter without danger of marring the wood, glass or other material forming such counter.

In the structure shown in Fig. 3, the 30 original box 7^{aa} containing the vendible goods may be slipped into the containing shell or cabinet from the rear of the same, and the cover of such box, which is usually employed as an advertising card, may be removed and inserted into a glazed frame 10^a 35 situated beyond the container or cabinet and disposed in the plane of the open box. In this instance, said frame 10^a as well as a cover 9^a for the container will be hinged to the latter on a common axis, indicated at 35.

The glazed cover 9^a is liftable for the purpose of gaining access to the goods of the original package disposed within the container or cabinet, and the rear hinged wall 4^a of the structure shown in Fig. 3, may be held in the closed position by the inner edge of the cover 10^a engaging the same, as clearly shown at 15^a in Fig. 3. As in the structure shown in Figs. 1 and 2, this cover 10^a may be retained in the open position by a hook 16^a hinged to the bottom of the container at 6^a and engaging an eye 17^a carried by said cover. Otherwise, the container shown in Fig. 3, may be mounted and supported in substantially the same manner as the container shown in Figs. 1 and 2, and may be operated in a precisely similar manner.

In Fig. 4, I have shown still another modified form of container substantially like that

of Fig. 3, in which the container proper is provided with a cover 9^b hinged at 35^b, which cover may be raised to gain access to the goods in the box 7^b. A glazed frame 10^b is also hinged on the same axis as the cover 9^b and held in the open position by a hook 16^b. 70 This frame 10^b may carry the title card or other advertisement relating to the goods to be dispensed.

While the several structures are provided with glazed covers for the cigar box and other lids, these glazed covers collapse on top of the main structure when such containers are shipped, as indicated by dotted lines in certain of the views, so that the size of the containers in the "knocked-down" condition 80 is no greater than ordinary containers which do not employ a glazed cover for receiving the box or other lids.

I claim:

1. The combination, in a supplemental 85 container for boxed goods, of a suitable inclosing shell, a pair of glazed covers hinged to said shell and foldable in substantially parallel relation over the same, one of said covers adapted to overlie vendible units in a box within said container while the other cover is adapted to overlie the cover of the 90 inclosed box, and hinged means for supporting said supplemental container with its covers in their active positions, the box cover 95 being held between said supporting means and the supplemental cover overlying the box cover.

2. The combination, in a supplemental 100 container for boxed goods, of a skeleton metal shell having glazed side walls, a pair of glazed covers hinged to said shell and foldable in substantially parallel relation to the same; one of said covers being adapted to overlie vendible units disposed in a box 105 within said container while the other cover is adapted to overlie the cover of said inclosed box, and means for supporting said container in an inclined position with its covers in their active positions.

3. The combination, in a supplemental 110 container for boxed goods, of a suitable inclosing shell, a pair of glass carrying frames forming covers hinged to said shell and foldable in substantially parallel relation to the same; one of said covers being adapted to overlie goods in a box disposed within said container while the other cover is arranged in substantially the same plane as the first and overlies the extended cover of said 115 inclosed box, a rear wall hinged to the bottom of said supplemental container, and means for supporting the container in an inclined position and maintaining said rear wall in the closed position.

4. In a container for boxed goods, the combination of a receptacle or container comprising a skeleton shell of metal to receive

an open box of goods to be vended and having glazed frames at the sides thereof, means for supporting the container at an angle with respect to a support or base upon which it 5 may be mounted with the box of vendible goods disposed at the same angle, framed glass covers carried by the container in the same plane as the open face of the box and

foldable in substantially parallel relation to the same; one of said glazed frames overlying and supporting the extended cover of the contained box, and means for maintaining the glazed frame carrying said cover in the open position; the other cover being freely movable to gain access to the vendible units. 10 15

EDWARD REUKAUF.
